LEO ROSEMAN, OF NEWARK, NEW JERSEY

FASTENER TAPE

Application filed November 29, 1929. Serial No. 410,427.

This invention relates in general to fastener tape in which the fastener elements, such as hooks and eyes, are inserted through perforations, slits or openings in a fold in the material of which the tape is made so that the strain on the fastener elements when in use is applied to the fabric directly.

Fastener tapes of this character now in use are formed of two folded and superposed 19 strips of material, one of which has the fold carrying the fastener elements while the other is stitched to the first strip to cover or conceal the slits or openings through which the fastener elements pass and to reinforce the tape. This construction is expensive and difficult to make, cumbersome to handle in applying it to a garment, and the attachment of the fastener elements is not strong enough to effectually withstand the 15 strains imposed thereon when the tape is in use. A similar construction is shown in my Patent No. 1,623,361.

One object of my invention is to obtain all of the advantages of this known construction, eliminate the disadvantages thereof, and to provide a stronger, less expensive, better appearing and more durable fastener tape.

Another object is to provide such fastener 30 tape comprising one strip of material folded in a novel and improved manner to receive and hold the fastener elements and conceal the slits or openings through which they are inserted.

35 A further object is to provide a fastener tape of this character having certain of the plies stitched together to obtain maximum strength of attachment of the fastener elements with a minimum of material and bulk; so that the tape will withstand more than twice the strain which can be sustained by known perforated or pierced tapes without pulling out of the fastener elements or tearing the material.

40 Other objects are to provide fastener tape of the character described which can be made economically in large quantities by automatic machinery; to provide fastener tape comprising a strip of fabric having a fold therein 45 provided with openings through which are

inserted fastener elements, said strip also having a pleat or Z-fold over the fastener elements to cover or conceal said openings; to provide such fastener tape wherein said pleat is stitched to the body of the tape transversely 55 of the fastener elements to securely fasten said elements on the tape, and to obtain other advantages and results as will be brought out by the following description.

Referring to the accompanying drawings 60 in which corresponding and like parts are designated throughout the several views by the same reference characters:

Figure 1 is a fragmentary top plan view of 65 fastener tape embodying my invention, showing the fabric folded and with a fastener eye inserted in the fabric and before stitching.

Figure 2 is a similar view after stitching, portions being broken away for clearness in 70 illustration.

Figure 3 is a like view with the upper garment attaching flap folded into its normal position.

Figure 4 is a top plan view of the fastener 75 tape showing the manner of securing it to the edge of a garment.

Figures 5, 6 and 7 are transverse vertical sectional views on the lines 5—5, 6—6, and 7—7 of Figures 1, 2 and 3 respectively.

Figure 8 is a view similar to Figure 7 showing the tape secured to a garment. 80

Figure 9 is a horizontal sectional view on the line 9—9 of Figure 7.

Figure 10 is a perspective view of a modified form of the invention. 85

Figure 11 is a view similar to Figure 7 showing a modification of the invention.

Figure 12 is a view similar to Figure 8 showing another form of the invention for attaching the tape to a garment in another 90 manner.

Figure 13 is a view similar to Figure 1 showing a modification of the invention wherein the tape is formed of two pieces of fabric, before stitching. 95

Figure 14 is a similar view after the plies of the fabric have been stitched, with portions broken away.

Figure 15 is a fragmentary perspective 100 view of the strips of fabric in their relative

positions before the fastener eyes are inserted.

Figure 16 is a view similar to Figure 14 showing another arrangement of the two strips of fabric.

Figure 17 is a view similar to Figure 15 showing the strips of fabric as used in the construction shown in Figure 16.

Figure 18 is transverse sectional view on 10 the line 18—18 of Figure 13.

Figure 19 is a similar view with the garment attaching flap folded into its normal position.

Figure 20 is a view similar to Figure 19 15 showing the construction illustrated in Figure 16.

Figure 21 is a view similar to Figure 1 showing a fastener tape including hooks instead of eyes.

20 Figure 22 is a transverse vertical sectional view on the line 22—22 of Figure 21.

Figure 23 is a view similar to Figure 21 after the plies have been stitched, showing the garment attaching flap broken away.

25 Figure 24 is a transverse vertical sectional view on the line 24—24 of Figure 23.

Figure 25 is a top plan view of the finished fastener tape, and

30 Figure 26 is a transverse vertical sectional view on the line 26—26 of Figure 25.

Specifically describing the embodiment of the invention illustrated in Figures 1 to 9 inclusive, the fastener tape includes a strip A of suitable material such as cotton fabric, which has a main portion 1 and one edge portion folded inwardly of said main portion at 2 to form a second ply 3 which is again folded outwardly at 4 to form another ply 5. The other edge portion is folded inwardly over the 35 main portion at 6 to form a ply 7 and is then folded outwardly at 8 to form another ply 9. The folds 4 and 8 are provided at spaced points with corresponding perforations, slits, 40 openings or pierced holes 10 through which are inserted or in which are formed eye fastener elements 11 with the base portions 12 disposed between the plies 3 and 5 and the eye portions 11 arranged upon the ply 7.

45 After the fabric strip has been folded as shown and described, the plies 1, 7 and 9 are stitched together by a line of stitching 13, while the plies 1, 3 and 5 are stitched together by a line of stitching 14, said stitches 14 passing over the bases of the eyes. Thereupon 50 the ply 9 is folded inwardly at 15 to form a garment attaching flap to receive the edge of a garment B between itself and the ply 3 as clearly shown in Figure 8 of the drawings. It will be observed that the folds 8 and 15 55 form a pleat or Z-bend which overlies the eye portion of the fastener element outwardly of the slits or openings 10 (see Figures 3 and 9), and this pleat or Z-fold is securely held in position by the line of stitching 13, whereby 60 the slits or openings 10 are entirely cov-

ered or concealed. At the same time, the line of stitching 13 greatly reinforces the attachment of the eye to the tape so that in this construction the eye will withstand more than twice the strain which can be sustained by known perforated or pierced fastened tapes without pulling out of the eye or tearing the fabric. Also, the Z-fold covers a considerable portion of the eye so that only a small part of the eye is visible. The tape is therefore pleasing to the eye, strong and durable and prevents gaping between the edges of the garment to which the tape is applied. The Z-fold brings strains applied to the fastener tape by a garment nearer to the eyes, and when it is desired to secure the garment over the tape instead of between the garment attaching flaps above described, the flap portion 9 may be cut off as at 16 in Figure 12, and the edge of the garment C superposed 80 upon the Z-fold.

In some instances it may be desirable to make the Z-fold or apply the line of stitching, after the garment attaching flap 9 is turned inwardly. Such a construction is 90 shown in Figure 10 where the line of stitching 17 is made after the garment attaching flap 18 has been folded inwardly. This produces the same effect in strength and appearance of the fastener tape, as is accomplished 95 by the construction shown in Figures 1 to 9 inclusive.

Should it be desirable to further reinforce the tape, for the attachment of a garment, I may insert a ply 19 of suitable fabric into the Z-fold and secure it to the tape by the line of stitching 13, as shown in Figure 11. This ply directly underlies the garment attaching flap 9.

For some classes of work, it may be desirable to have the garment attaching flap 9 of different material than the body portion of the tape, for example, silk, to provide a finished appearance. For such cases the garment attaching flap 9 of the construction shown in Figures 1 to 9 inclusive is cut away at 19, and an extra strip 20 of suitable material, such as silk, has one edge laid along the portion 19 of the tape. The folds 4 and 8 of the strip A are provided with the openings 10 as in the construction shown in Figures 1 to 9, and the strip 20 is formed with corresponding openings or slits 21. The eye is passed through all three of the slits. A line of stitching 22 corresponding to the stitching 13 connects the plies 1, 7, 19 and 20, as shown in Figures 14 and 18, and when the strip 20 is folded inwardly over the tape as shown in Figure 19 the said strip serves as a garment attaching flap like the flap 9. The Z-fold is still present, but is formed of two pieces of material in this construction instead of one piece as in the hereinbefore described construction. The advantages and functions of this construction are substantial- 125 130

ly the same as that of the construction shown in Figures 1 and 9.

Also it is possible to insert the additional strip of material between the folds 4 and 8 instead of along the portion 19 as shown in Figures 13, 15 and 19. Such a construction is shown in Figures 16, 17 and 20 where the additional strip 23 is arranged between the folds 4 and 8 and has slits or openings 24 through which the eyes are inserted. A line of stitching 25 connects the plies 1, 7 and 23, and the strip 23 is folded inwardly over the tape to provide a Z-fold as shown in Figure 20.

It is also possible to embody my invention in hook fastener tape, that is, tape having hooks thereon instead of eyes. Such a construction is shown in Figures 21 to 26, inclusive, wherein the tape comprises a strip 20 D of fabric having a main portion 26 and plies 27, 28, 29 and 30 arranged in relations identical to those of the plies 1, 3, 5, 7 and 9 of the construction shown in Figures 1 to 9. Folds 31 and 32 are formed between the respective plies 27, 28, 29 and 30, and these folds have slits or openings 33 through which the hooks 34 are inserted, just as are the eyes 11. It is preferable to insert the hooks before the bills are bent up. In other words, the hooks are inserted in flat condition as clearly shown in Figures 21, 22 and 23. A line of stitching 35 connects the plies 26, 29 and 30, and the ply 30 is folded inwardly over the tape to provide a Z-fold or pleat which conceals the slits or openings 33 and strengthens the tape, exactly as does the Z-fold and line of stitching 13 in the construction shown in Figures 1 to 9 inclusive. Preferably the line of stitching 35 is interrupted at each hook 40 to form lateral stitches 36 and longitudinal stitches 37 across the base portions 38 of the hooks, as clearly shown in Figures 23 and 24 of the drawings. This form of stitching is old and well-known in the art.

The bills 39 of the hooks may be formed at any suitable point in the manufacture of the tape, and by any suitable means, the bills preferably being bent upwardly as shown in Figures 25 and 26 after the ply or garment attaching flap 30 has been folded inwardly as shown in Figure 26. This tape has all the advantages of the eye tape shown in Figures 1 to 20 inclusive, and of course the modifications of the eye tapes hereinbefore described may also be applied to the hook tape.

Obviously the details of construction of the tape may be modified or changed by those skilled in the art without departing from the spirit or scope of the invention, and therefore I do not desire to limit the construction and use of my invention except as may be required by the following claims when construed in the light of the prior art.

Having thus described my invention, what I claim is:

1. A fastener tape comprising a strip of fabric having a main portion with one edge portion folded inwardly of said main portion to form a second ply then folded outwardly to form a third and narrower ply, the second-mentioned fold having an opening, and a fastener element passing through said opening and comprising a base and an engaging portion, said engaging portion being disposed between said second and third plies and exposed beyond the third ply, whereby said third ply overlies and conceals said opening. 70

2. A fastener tape comprising a strip of fabric having a main portion with one edge portion folded inwardly of said main portion to form a second ply and then folded outwardly to form a third and narrower ply and then inwardly to form a fourth ply, the second-mentioned fold having an opening, and a fastener element inserted through said opening comprising a base and an engaging portion, said engaging portion lying between said second and third plies and exposed beyond the third ply, whereby said third and fourth plies overlie and conceal said opening. 80

3. The fastener tape set forth in claim 1 wherein the first, second and third plies are stitched together. 90

4. The fastener tape set forth in claim 1 with the addition of a line of stitching longitudinally of said strip connecting the first, second and third plies and crossing the engaging portion of said fastener element. 100

5. The fastener tape set forth in claim 2 wherein the first, second and third plies are stitched together. 105

6. The fastener tape set forth in claim 2 with the addition of a line of stitching longitudinally of said strip connecting the first, second and third plies and crossing said fastener element. 110

7. The fastener tape set forth in claim 2 with the addition of a line of stitching longitudinally of the strip connecting all of said plies.

8. A fastener tape comprising a strip of fabric having its edge portions folded inwardly upon itself into contact with each other and the free edge of each portion folded outwardly, the last-mentioned folds having registering openings, and a fastener element comprising a base and an engaging portion extending through said openings with the base portion disposed between one edge portion and one free edge and the engaging portion exposed on the face of the other edge portion, the other free edge being again folded inwardly to form a Z-shaped pleat overlying said fastener element between its base and engaging portion and concealing said openings. 115

120

125

130

9. The fastener tape set forth in claim 1 with the addition of a line of stitching longitudinally of said strip connecting the first, second and third plies and crossing the engaging portion of said fastener element and another longitudinal line of stitching connecting the base of the fastener element to said strip.

10. The fastener tape set forth in claim 8 with the addition of a line of stitching longitudinally of the strip through said Z-shaped pleat.

11. The fastener tape set forth in claim 8 with the addition of a line of stitching longitudinally of the strip through said Z-shaped pleat and another longitudinal line of stitching crossing the base of said fastener element and connecting the first-mentioned edge portion and the corresponding free edge.

12. The fastener tape set forth in claim 1 with the addition of a longitudinal line of stitching connecting the base of the fastener element to said strip.

13. A fastener tape comprising a strip of fabric having a main portion with one edge portion which is folded inwardly of said main portion to form a second ply and then folded outwardly to form a third ply and then may be turned inwardly to form a fourth ply in overlying relation to the other edge portion of said strip, the second-mentioned fold having an opening, and a fastener element inserted through said opening comprising a base and an engaging portion, said engaging portion lying between said second and third plies and being exposed beyond the third ply when said edge is folded to form a fourth ply, whereby said third ply overlies and conceals said opening and said fourth ply and the second-mentioned edge of said strip may receive the edge of a garment between them.

14. A fastener tape comprising a strip of fabric having a main portion with one edge portion folded inwardly of said main portion to form a second ply, and then folded outwardly to form a third and narrower ply, the second-mentioned fold having an opening, and a fastener element passing through said opening and comprising a base and an engaging portion, said engaging portion being disposed between said second and third plies and exposed beyond the third ply, whereby said third ply overlies and conceals said openings, and a second strip of fabric connected to the edge of said third ply to form a garment attaching flap.

15. A fastener tape comprising a strip of fabric having a main portion with one edge portion folded inwardly of said main portion to form a third and narrower ply, the second-mentioned fold having an opening, and a fastener element passing through said opening and comprising a base and an engaging portion, said engaging portion being disposed

between said second and third plies and exposed beyond the third ply, whereby said third ply overlies and conceals said opening, and a second strip of fabric connected to the edge of said third ply to form a garment attaching flap and having an opening through which passes the engaging portion of said fastener element.

16. A fastener tape comprising a strip of fabric having a main portion with one edge portion folded inwardly of said main portion to form a second ply and then folded outwardly to form a third and narrower ply, the second-mentioned fold having an opening, and a fastener element passing through said opening and comprising a base and engaging portion, said engaging portion being disposed between said second and third plies and exposed beyond the third ply, whereby said third ply overlies and conceals said opening, and a second strip of fabric with one edge disposed between the main portion and second-mentioned ply and having an opening registering with the opening in said second-mentioned fold through which passes the engaging portion of said fastener element.

17. A fastener tape comprising a strip of fabric having a main portion with one edge portion folded inwardly of said main portion to form a second ply and then folded outwardly to form a third and narrower ply, the second-mentioned fold having an opening, and a fastener element passing through said opening and comprising a base and an engaging portion, said engaging portion being disposed between said second and third plies and exposed beyond the third ply, whereby said third ply overlies and conceals said opening, a second strip of fabric having an opening in register with said opening in said second-mentioned fold through which passes said fastener element, and a line of stitching longitudinal of said tape connecting said first, second and third plies and said second strip.

LEO ROSEMAN.
